Application March 22, 1939, Serial No. 263,562
In Great Britain April 6, 1938

13 Claims. (Cl. 226—2)

This invention is for improvements in or relating to packing machines by means of which an article is inserted into a box of the kind in which a lid is connected to one side of the box and a closure flap is connected with the side of the lid opposite that side of the lid which is connected to the box. Such boxes will be referred to in the appended claims as "boxes of the kind described."

The term "article" when used herein and in the appended claims is to include a batch of articles, such for example as a batch of cigarette packages.

It has hitherto been customary in machines for inserting an article into a box of the kind described to feed to the machine the boxes already opened to receive the article and because it is not possible satisfactorily to feed the opened boxes automatically from known magazines the boxes have previously been fed manually one at a time to the machines.

The term "fanwise arranged boxes" used herein and in the appended claims means an arrangement of a succession of boxes in which all the boxes of the succession are nested by inserting only one and the same end of each box into the corresponding end of the next box. Thus the bottoms of successive boxes converge and the angles formed by the bottoms of a plurality of successive boxes are all arranged to diverge outwardly and the lids of the nested boxes all lie on the same side of the nest.

It is an object of the invention to provide mechanism whereby fanwise arranged boxes of the kind described can be fed to a box filling machine. This object is achieved according to one aspect of the invention by means of a support rotatable in one direction about a fixed axis and adapted to move fanwise arranged boxes towards a transfer device arranged to engage the lid or the closure flap of the leading box and to move the box transversely to the direction of movement of the support and away from the axis of rotation of the support to separate the leading box from the others.

A further object of the invention is to provide mechanism for positioning a box accurately in a filling position, and this object is obtained by placing the box on a movable platform which tends to move the box away from the filling position and providing means movable into and out of the path of a box on the platform, such means being adapted to locate the box in the filling

position and to retain the box in such position until the box is filled.

The invention will be described by way of example with reference to the accompanying drawings in which—

Figure 1 is an elevation of an apparatus for feeding opened boxes of the kind described, a part of the apparatus at the right hand side of the figure being broken away.

Figure 2 is a plan of the upper part of Figure 1, and shows the parts which were omitted from Figure 1.

Figure 3 is a view, partly in section, taken in the direction of the arrow A, Figure 1, some parts being omitted for the sake of clarity.

Figure 4 is a perspective view of an opened box of the kind described.

Figures 5 and 6 show an elevation and plan respectively of a box locating device which has been omitted from Figure 2 for the sake of clearness.

Like reference numerals refer to like parts throughout the specification and drawings.

Referring to the drawings, opened boxes as shown in Figure 4 are placed fanwise on a rotatable support. As can be seen from Figure 4, a box comprises a body *a*, a lid *b* connected to one side of the body portion and a closure flap *c* which is connected by a score or crease line *e* with the side of the lid opposite that side of the lid which is connected to the body of the box. The ends of the box are also provided with small flaps *d*. The rotatable support comprises a disc *1* mounted for rotation in one direction about a fixed axis. The disc *1* is rotatably mounted in a bearing *2* which is fixed to a bracket *3* which latter is fixed to the end face of a bed *4* which forms part of a box filling machine.

The fanwise arrangement of the boxes on the support is indicated in Figure 2 in which figure the leading box is shown in lines consisting of dashes separated by three dots, while the next box is shown by lines consisting of dashes separated by two shorter dashes, and the third box is shown by alternate long and short dashes. It will be appreciated that further boxes are similarly arranged in this fanwise manner until the major portion of the disc is covered by fanwise arranged boxes, and as boxes are fed from the position occupied by the leading box, more boxes can be added by the operator in fanwise arranged groups of say ten boxes. With the apparatus being described the fanwise arranged boxes are

placed on the rotatable support so that the lids and closure flaps of the boxes are uppermost.

A guard 5 carried on a support 6 (Figure 2) is mounted adjacent to the rim of the disc and serves to prevent the boxes being thrown too far outwardly by centrifugal force during rotation of the disc 1.

From Figure 2 it will be seen that the closure flap c of the leading box has been caused by the rotation of the disc 1, which moves in the direction indicated by the arrow, to engage a locating device which consists of a fixed plate 7 to which is secured a pair of converging guide plates 8 and 9 arranged substantially in the form of a V. This V may be seen more clearly from Figure 1 where the guides are sectioned to show their shape.

The closure flap c of the leading box is guided by the guide plates 8 and 9 into engagement with the plate 7 and the engagement of the closure flap with the plate 7 causes the boxes on the support 1 to be arrested.

It is sometimes found that if the guard 5 is rigid the boxes have a tendency to jam against the guard 5 when the boxes on the support are arrested, with the result that the feeding of the boxes by the support may be disturbed. To avoid this difficulty the guard 5 is flexible and is fixed to the support 6. The end of the guard which is nearest to the guide plates 8 and 9 is connected with a lever 167 pivoted at 168 to a bracket 169. The lever 167 carries a roller 170 which engages a cam 171 fixed to a pulley 56 and the cam is arranged to cause the guard to be vibrated so as to be moved away from the outer ends of the boxes when the support operates to move the boxes forwardly after a box which has been located by the guide plates 8 and 9 has been removed from the fanwise arrangement on the support. The roller 170 is held in engagement with the cam 171 by a spring 172.

Since the boxes may have moved slightly relatively to one another due to centrifugal force each box after it has engaged the plate 7 is engaged by a first adjusting stop comprising a plate 78 (Figures 5 and 6) which is fixed to a lever 79. The lever 79 is pivoted to a spindle 80 mounted in a bearing fixed to the plate 7. The upper end of the spindle 80 has a lever 81 fixed thereto and the lever 81 is connected to a cam link 82 on which is mounted a roller 83 (Figure 1) which engages a cam 84 fixed to the front face of a rotatable segmental disc 10. As the segmental disc 10 rotates the link 82 is moved to and fro by the cam in conjunction with a spring 85 and the plate 78 is moved thereby from the position shown in full lines in Figure 6 to the position shown in broken lines. When the leading box engages the plate 7 the plate 78 is in the position shown by broken lines in Figure 6 and the plate 78 is then moved into the position shown in full lines, thus engaging the inside of the rear end of the box and, if necessary, moves the box rearwardly, that is to the right of Figure 1, until the box occupies the desired position as determined by the extent of rearward movement of the plate 78.

When the leading box has, in the manner described above, been adjusted and located in the position shown in Figure 2 it is located relatively to a transfer device and the closure flap c of the box is disposed between the peripheries of a rotatable segmental disc 10 and a roller 11 which comprise the transfer device. The segmental disc

10 is positively rotated in the direction indicated in Figure 1 and co-operates with the roller 11 to move the leading box transversely to the direction of movement of the disc 1 and away from the axis of rotation of the disc 1 so as to separate the leading box from the others. The closure flap c is positioned between the segmental disc 10 and the roller 11 while that part of the segmental disc which is of smaller diameter is opposed to the roller 10.

The transfer device moves the box lengthwise in the direction of the arrow B (Figure 2), so that the underside of the closure flap c is moved into engagement with a narrow support 12 disposed in a horizontal plane parallel to the plane of the rotatable disc.

As will be seen from Figure 3, the support 12 comprises a bar of triangular section having an extension 13 projecting above the flap engaging surface and against which the closure flap of the box is located.

Above the support 12 there is provided another transfer device comprising a positively rotated segmental disc 14 which co-operates with a roller 15. This second transfer device is spaced apart from the preceding transfer device in the direction of movement of the box by the transfer devices, and the box is moved by the transfer devices substantially into a box filling position (see dot and dash lines indicating the box in this position in Figure 1).

When the box has reached this position, the closure flap is retained in engagement with the support 12 and the body of the box together with the lid is caused to turn about the score line e so that the body is moved through substantially 90° to the position shown in Figure 3, at which position the bottom of the box rests on a platform which, in the example shown, consists of a travelling band or belt 16.

While the box is in this position an article may be moved downwardly in the direction of the arrow C into the box. It will also be seen from Figure 3 that the lid b is inclined away from the open end of the box towards the closure flap so as not to impede the downward movement of an article into the box.

The mechanism for inserting an article into a box forms no part of the present invention, but preferably comprises mechanism as described and claimed in the specification accompanying co-pending United States application Serial No. 263,563, of even date.

In order to assist in locating the box in its proper position on the platform 16 there are provided various stops and movable flaps which act in the following manner.

The closure flap c is gripped between the segmental disc 14 and the roller 15, until the feeding movement ceases and until the box is moved completely off of the rotatable support 1 it is in the horizontal position shown in full lines in Figure 3. The weight of the box, once it is moved completely off of the support 1, tends to turn the lid and the body about the score line e and this movement of the body and the lid is assisted by an oscillating flap 17. In order to retain the closure flap c in position on the support 12 after the second transfer device ceases to grip the flap, a flap engaging device comprising small freely rotatable rollers 160 are mounted above the support 12 and co-operate therewith frictionally to engage the closure flap and to retain the closure flap in position while the body portion of the box

is being turned about the score line *e*. The flap *17* is fixed to a spindle *18* which is supported in bearings *19* depending from a support bar *20* which also carries the spindles of the segmental discs *10* and *14*. The support bar *20* is carried by a plate *21* fixed to one end of the bed *4* and a bracket *22* fixed to the upper surface of such bed. The spindle *18* is also supported in a bearing *23* fixed to the bracket *22* and carries at its outer end a lever *24* to which is connected a link *25* which is bent as shown in Figure 3 so that it has a right angled extension. The end of the extension is pivoted to a cam lever *26* carrying a roller *27* which engages with a cam *28* and the other end of the lever *26* is pivoted at *29* to a bracket *30* fixed to the bed *4*. As the cam *28*, which is driven as hereinafter described, is rotated the flap *17* is caused to oscillate through approximately 90° thus causing the box body and lid to be positively bent about the front edge of the triangular bar and brought into position above the belt *16*. The support *12* is slotted at *88* (see Figure 1) to clear the box flaps *d* during this movement.

An oscillating pusher element *31* is provided to engage the box body and push it into position above the belt *16*, the side of the box opposite that engaged by the pusher element being pressed against an angle stop *32*, see Figure 3.

The method of operating the pusher element *31* will be described later.

As it is desirable to locate the box accurately in the filling position the second transfer device is arranged to move the leading end of the box slightly past the filling position and the box is then moved rearwardly towards the filling position. This rearward movement is effected by a second adjusting stop comprising a member *33* which is pivoted at *34* to the support bar *20* and which is moved by a cam *35* and an angle piece *164* which is mounted on a bar *161* slidably carried on the plate *17*. The bar *161* (see Figure 1) is carried on guide pins *162* and *163* attached to the hinge pieces of the plate *17* and is urged towards the member *33* by a spring *165*. The cam engages a roller *86*, and a spring *87* returns the member *33*. The member *33* is caused to engage with the angle piece *164* and the latter engages the leading edge of the box lid and pushes it back slightly beyond its correct position, after which a stop *36* moves into the path of the box which is then carried along by the movement of the belt *16*, which latter travels in the direction indicated, until it is stopped by said stop *36*, when the box is in its proper position for receiving the article. The angle piece *164* swings with the plate *17* and is therefore moved out of the path of a box when the latter is moved by the belt *16* away from the filling position. Rearward movement of a box by the angle piece *164* and member *33* causes the leading flap *d* to be engaged by a downwardly projecting element (not shown) which causes the flap *d* to be moved away from the open end of the box into a position such as that indicated in Figure 1 so that the flap does not interfere with the subsequent filling of the box. The flap *d* at the rear end of the box is also moved into a position so as not to interfere with the filling of the box, and this movement is also affected by downwardly projecting elements one of which comprises a tapered guide *166* which drags the rear flap *d* backwardly as the box is being swung downwardly towards the filling position by the

plate *17*. When the box is in the filling position the rear flap *d* is not engaged by the guide *166* but by a further downwardly directed element (not shown).

5 The pusher element *31* is fixed to a lever *37* which is in turn fixed to a spindle *38* mounted in a bearing *39* fixed to the base of the bed. A cam *40* driven in the manner hereinafter described engages a roller *41* mounted on the lever *37* and operates the pusher element *31* at the desired intervals in conjunction with a spring *42*.

10 The stop *36* is carried on a lever *43* fixed to the spindle *38* and operated by a cam *44* which engages a roller *45* on the lever *43* and in conjunction with a spring *46* operates the stop *36* at the desired intervals.

15 The machine is driven from a shaft *47* which is rotated from any convenient source of power. The shaft *47* is supported in a bearing *48* attached to the back of the bed *4*, see Figure 3, and has a bevel gear wheel *49* at the end adjacent to such bearing, which bevel gear wheel engages with a further bevel gear *50* mounted on a cross shaft *51* supported in bearings in the bed *4*.

20 The other end of the shaft *51* has a bevel pinion *52* engaging a bevel gear wheel *53* fixed to a cam shaft *54* supported in bearings *55* fixed to the front face of the bed. An extension of the cam shaft *54* has a V-pulley *56* fixed to it which drives a pulley *57* fixed to the base of the disc *1* by a belt *58* which passes over jockey pulleys *59*.

25 On the spindle *51* at a point near the bevel gear *50* is fixed a sprocket *60* which drives an upper sprocket *61* by means of a chain *62*, the sprocket *61* being fixed to a spindle *63* which is mounted in a bearing bracket *64* fixed to the bed of the machine. The other end of the spindle *63* carries a small sprocket *65* which drives the segmental discs *10* and *14* by means of a chain *66* which passes over sprockets *67* and *68* fixed to the segmental discs; the chain also passes over jockey's *69*, Figure 1. It will be observed from Figures 1 and 2 that the cam *35* is fixed to the spindle *63*.

30 From Figure 1 it will be seen that the cam shaft *54* carries the cams *40*, *44* and *28*. It also carries another cam *70* which engages with a roller *71* fixed to one end of a lever *72* pivoted at *73* to a bracket fixed to the bottom of the bed. The other end of the lever *72* is connected by a link *74* to plates *75* which form supports for the roller *76* around which the belt *16* passes. The remote ends of the frame *75* are pivoted at a point *77* which is several feet away from the parts shown in the drawings, and as the cam *70* rotates the belt *16* is lowered from the position shown for a distance sufficient to permit the body portion of the box freely to be swung into position above the belt before being engaged by the belt.

35 From the foregoing description it will be seen that the first and second adjusting stops are movable in timed relationship with the transfer device, the stop *36* is movable in timed relationship with the pusher element *31* and the second adjusting stop, the platform *16* is movable towards and away from the filling position in timed relationship with the movements of the pusher element *31*, and the second adjusting stop is movable in timed relationship with the transfer device.

40 A box on the belt *16* is released by the stop *36* after a box has been filled, and the removal of

the stop 36 from the path of the box permits the belt 16 to move the box in the same general direction as that in which it is moved by the transfer device and away from the filling position.

What we claim as our invention and desire to secure by Letters Patent is:

1. In apparatus for filling boxes of the kind described, a support for fanwise arranged boxes, said support being continuously rotatable in one direction about a fixed axis, a transfer device adapted to engage a closure element of the leading box on the support and to move the box transversely to the direction of movement of the support and away from the axis of rotation of the support to separate the leading box from the others, and a locating device to locate the closure flap of the leading box in position to be engaged by the transfer device and substantially to arrest the movement of the boxes on the support.

2. In apparatus for filling boxes of the kind described, a support for fanwise arranged boxes, said support being continuously rotatable in one direction about a fixed axis, a transfer device adapted to engage a closure element of the leading box on the support and to move the box transversely to the direction of movement of the support and away from the axis of rotation of the support to separate the leading box from the others, a locating device to locate the closure flap of the leading box in position to be engaged by the transfer device and substantially to arrest the movement of the boxes on the support, and a first adjusting stop movable in timed relationship with the transfer device to engage the inner side of the rear end face of a box engaged by the locating device and to move the box rearwardly to position the box relatively to the transfer device.

3. In apparatus for filling boxes of the kind described, a support for fanwise arranged boxes, said support being rotatable in one direction about a fixed axis, a transfer device to engage the leading box on the support and to move the box transversely to the direction of movement of the support to separate the leading box from the others, a flap engaging device to engage and retain in position the closure flap of a box delivered by said transfer device, and a pusher element to engage the body portion of a box so retained and to move the body portion of the box towards a filling position.

4. In apparatus for filling boxes of the kind described, a support for fanwise arranged boxes, said support being rotatable in one direction about a fixed axis, a transfer device to engage the leading box on the support and to move the box transversely to the direction of movement of the support to separate the leading box from the others, a platform to engage the bottom of a box at a filling position, a flap engaging device arranged frictionally to engage and retain in position the closure flap of a box delivered by said transfer device, and a pusher element to engage the body portion of a box so retained and to swing said body portion about the connection between the lid and the closure flap of the box so that the body portion is move towards the filling position and above said platform.

5. In apparatus for filling boxes of the kind described, a support for fanwise arranged boxes, said support being rotatable in one direction about a fixed axis, a transfer device to engage the leading box on the support and to move the box transversely to the direction of movement of the support to separate the leading box from the

others, a platform to engage the bottom of a box at a filling position, a flap engaging device arranged frictionally to engage and retain in position the closure flap of a box delivered by said transfer device, and a pusher element to engage

5 the body portion of a box so retained and to swing said body portion about the connection between the lid and the closure flap of the box so that the body portion is moved towards the filling position and above said platform, said platform being movable towards and away from the filling position in timed relationship with the movements of said pusher element to permit the body portion of the box freely to be swung into position above the platform.

10 6. In apparatus for filling boxes of the kind described, a support for fanwise arranged boxes, said support being rotatable in one direction about a fixed axis, a transfer device to engage the leading box on the support and to move the box

20 transversely to the direction of movement of the support to separate the leading box from the others, an endless band adapted to support a box in the filling position and to move the box away from said position after the box is filled, a flap

25 engaging device arranged frictionally to engage and retain in position the closure flap of a box delivered by said transfer device, a pusher element to engage the body of a box so retained and to swing the body about the connection between

30 the lid and the closure flap of the box so that the body is moved towards the filling position and above said band, and means operative in timed relationship with the pusher element to swing said band upwardly and downwardly to permit

35 the box body freely to be swung into position above said band.

7. In apparatus for filling boxes of the kind described, a transfer device to feed the leading end of a box slightly past the filling position, an adjusting stop to engage the leading end of the box and to move the box rearwardly so that the leading end of the box occupies a position in advance of the position to be occupied at the filling position, an endless movable band to support the box and to move the box towards the filling position, and a stop operative in timed relationship with said adjusting stop to engage the leading end face of an adjusted box and thereby to arrest the movement of the box by said band until the box is filled and to locate the box in the filling position.

8. In apparatus for filling boxes of the kind described, a transfer device to separate the leading box from a fanwise arrangement of boxes and to move the separated box towards a filling position, a rotatable support to move fanwise arranged boxes towards the transfer device, an endless continuously movable band to move a box away from the filling position and to support the box at such position, and means to locate a box in the filling position.

9. In apparatus for filling boxes of the kind described, a transfer device to separate the leading box from a fanwise arrangement of boxes and to move the separated box towards a filling position, a rotatable support to move fanwise arranged boxes towards the transfer device, an endless continuously movable band to move a box away from the filling position and to support the box at such position, means to move said band in an upward and a downward direction to permit the body portion of a box to be moved above the band, and means to locate a box in the filling position.

10. In apparatus for filling boxes of the kind described, a transfer device to separate the leading box from a fanwise arrangement of boxes and to move the separated box towards a filling position, a rotatable support to move fanwise arranged boxes towards the transfer device, an endless continuously movable band to move a box away from the filling position and to support the box at such position, an adjusting stop to move the box in a direction reverse to the direction of movement of said band to a position such that the leading end of a box is disposed in advance of the filling position, and a stop operative in timed relationship with said adjusting stop to engage the leading end of an adjusted box and thereby to locate the box in the filling position and to retain the box in such position during the filling of the box.

11. In apparatus for filling boxes of the kind described, a rotatable support for fanwise arranged nested boxes, a transfer device movable in a plane different from the plane of the rotatable support, and means for rotating said support to move said boxes in a circular path with their nested ends nearest the axis of rotation, and to successively position the leading elements of said boxes at the plane of movement of said transfer device, the latter having means to successively engage the boxes of said fanwise arrangement and move them transversely of said path and away from said axis, whereby said boxes are successively disengaged from said fanwise arrangement without disturbing the remaining boxes.

12. In apparatus for filling boxes of the kind

described, a rotatable support for fanwise arranged nested boxes, a transfer device movable in a plane different from the plane of the rotatable support, and means for rotating said support to move said boxes in a circular path with their nested ends nearest the axis of rotation, and to successively position the closure elements of said boxes at the plane of movement of said transfer device, the latter having means to successively engage closure elements of said respective boxes and to move said boxes transversely of said path and away from said axis, whereby said boxes are successively disengaged from said fanwise arrangement without disturbing the remaining boxes.

13. In apparatus for filling boxes of the kind described, a rotatable support for fanwise arranged nested boxes, a transfer device movable in a plane different from the plane of the rotatable support, and means for rotating said support to move said boxes in a circular path with their nested ends nearest the axis of rotation, and to successively position the leading elements of said boxes at the plane of movement of said transfer device, the latter having means to successively engage the boxes of said fanwise arrangement and move them transversely of said path and towards a filling position, whereby said boxes are successively disengaged from said fanwise arrangement without disturbing the remaining boxes, and means to successively locate said boxes at said filling position.

DESMOND WALTER MOLINS.

FRANK PARRY.
